ATTACHMENT TO IRONING MACHINES

Walter A. Hoch, Forest Hills, N. Y., assignor to
New York Pressing Iron Co. Inc., New York,
N. Y., a corporation of New York

Application January 17, 1939, Serial No. 251,315

4 Claims. (Cl. 38—141)

My invention relates to a new and improved attachment to an ironing machine.

One of the objects of my invention is to provide a simple attachment for machines which are used for ironing shirts, in order to hold the neckband of the shirt upright and in proper position relative to the body of the shirt.

Another object of the invention is to provide a clamping device for the neckband of a shirt, which will function without springs and which will have an inherent resilient clamping action.

Another object of the invention is to provide a device which has an operating head which is readily accessible, so that the attendant can operate the device conveniently with one hand.

Other objects of my invention will be set forth in the following description and drawings which illustrate a preferred embodiment thereof, it being understood that the above statement of the objects of my invention is intended generally to explain same without limiting it in any manner.

Fig. 1 is a side elevation showing the attachment in the closed or clamping position.

Fig. 2 is a side elevation showing the attachment in the open or non-clamping position.

Fig. 3 is an end elevation taken at the left-hand side of Fig. 1.

Fig. 4 is a top plan view of Fig. 1. In this view the knob or head of the device has been omitted.

Fig. 5 is a sectional view on the line 5—5 of Fig. 3. This shows certain different relative positions of the parts, respectively in full lines and in broken lines.

Referring to Figs. 1 and 2, the device has a base 2 which is provided with an upstanding integral abutment flange or wall 1. Said wall 1 has a reentrant portion 14, which is spaced from the clamp C, when said clamp is in operative position. At its rear, the base is provided with a bracket of angular shape, which has upstanding integral ribs 3 and 3a.

An upstanding guide arm 4, having a curved guide slot 5, is provided with a base 6 which is connected to an upstanding projection of the base 2 by means of screws 7. The upstanding arm 8 has a base 9 which is connected to the same upstanding projection of base 2, by means of screws 10. The rib 3 is integral with a fixed bearing-sleeve 11. A pin 12 passes through said bearing-sleeve 11 and through second and third sleeves 14 and 17. The sleeves 14 and 17 are connected by an integral member 30. Said member 30 has an integral angular arm 31 which is connected to one end of link 22 by pivot pin

21a. Said member 30 is recessed adjacent arm 27. The second sleeve 14 is integral with a first clamp-arm 15. A second clamp-arm 16 is integral with the third sleeve 17. The pivot pin 12 also passes through a fourth sleeve 18, whose function will 5 be later described.

The U-clamp C is made of springy steel or other resilient material. The shape of a portion of said clamp C is substantially the same as the shape of a portion of the abutment wall 1, so that 10 slight distortion of the resilient clamp C will effectively clamp the neckband of the shirt against abutment wall 1. The other parts of the device are preferably made of rigid metal, although they may be made of rigid or resilient 15 material of any kind, if desired. The clamp C is rigidly connected to the forked bottom ends of the arms 15 and 16 by any suitable detachable fastening means, so that clamp C cannot turn relative to arms 15 and 16. The device includes 20 a first arm which consists of two aligned identical members 19, which are connected to each other by means of a pivot pin 20, whose shank fits closely and slidably in the guide-slot 5.

As shown in Fig. 1, the outer ends of the members 19 of said first arm are connected by means of a pivot pin 21 to the link 22. Said pivot pin 21 is connected to said link 22, intermediate the ends of said link. The upper end of said link 22, referring to Fig. 1, is connected by means of a 25 pivot pin 23 to the legs 24 of a second and fork-shaped arm which has legs 24, and whose upper integral end is connected by means of a pivot pin 26 to the forked end of an integral extension-arm 27 of the fourth sleeve 18. Said extension or third 30 arm 27 has a threaded shank 28 releasably connected thereto, and an operating knob 29 is releasably connected to said threaded shank 28. When the device is in the inoperative position shown in Fig. 2, the shank of the pivot pin 20 35 abuts the upper end-wall of the slot 5. The members 19 of the first arm are then substantially parallel to the legs 24 of the second arm, so that the longitudinal axes of said arms are then coincident or substantially coincident.

The resilient clamp C is spaced a substantial distance from the upstanding clamping wall or clamping flange 1, when the device is in said inoperative position. The neckband of the shirt can therefore be readily adjusted so as to abut 40 said wall or flange 1.

When the device is in the closed position illustrated in Fig. 1, and the clamp C is held stationary relative to the flange 1, the third arm 27 and its integral sleeve 18 can be rocked a limited 45 50 55

distance relative to the fixed sleeve 11, and the second and third sleeves 14 and 17. The first and second arms 19 and 24 and the link 22 can therefore be turned through a small arc, without shifting the clamp C upwardly relative to the flange 1. This explanation is given merely to explain the connections of the parts, because in actual use, the third arm 27 and clamp C are moved in unison away from the position shown in Fig. 1.

10 The operation of the device is as follows:

When the parts are in the position shown in Fig. 2, and the third arm 27 and its integral sleeve 18 are turned counterclockwise around the axis of pivot member 12, the second arm 24 and the link 22 exert a thrust upon the angular or fourth arm 31 of the member 30, so that the second and third sleeves 14 and 17 are caused to turn in unison with said third arm 27. When the parts are in the position shown in Fig. 2, it is possible to turn the second arm 24 relative to the third arm 27, so as to turn the first and second arms 19 and 24 from the position shown in Fig. 2. It is thus possible to turn the arm 27 and then to turn the forked end of the link 22 relative to the angular arm 31, around the pivot 21a, so that the arm 27 can be turned counterclockwise while the clamp C is held stationary. However this is stated merely to further explain the relations between the various parts, because in actual use the combined thrust of the second arm 24 and of the link 22 causes the member 30 and its integral sleeves 14 and 17 to turn in unison with the third arm 27. During said turning movement, the shank of the pin 20 slides in the guide-slot 5, until said shank abuts the bottom end-wall of said guide-slot 5. The clamp C is then inclined about 45° to the base 2 and the longitudinal axes of the first and second arms 19 and 24 are then inclined to each other at an angle which is a little greater than 90°. The members 19 of the first arm are then inclined upwardly relative to the horizontal plane.

When the third arm 27 is turned further in the counterclockwise direction, the members 19 of the first arm turn clockwise relative to the upstanding guide arm 4 and the angle between the arms 19 and 24 is decreased. The clamp C first abuts the flange 1 at two spaced portions thereof, which are spaced substantially equally from the member 8. The initial contacting position of clamp C is shown in full lines in Fig. 5, and the corresponding positions of other parts are also shown in full lines. In this position the members 19 of the first arm are substantially horizontal and the longitudinal axis of the second arm 24 makes an acute angle with the longitudinal axis of the first arm 19. The upper end of the guide arm 4, including the upper end-portion of the slot 5, is then located above and between the legs 24 of the second arm. In this initial operative position of the clamp, the link 22 is inclined upwardly, so that its left-hand end is higher than its right-hand end. Downward pressure is then exerted upon the knob 29 so that it is moved from the full-line position shown in Fig. 5 to the broken-line position shown in Fig. 5. The clamp C is then forced from the initial full-line position shown in Fig. 5, downwardly to the final clamping broken-line position. The members 19 are thus turned until their longitudinal axis is inclined downwardly. The first and second arms 19 and 24 and the link 22 are thus locked in closing and clamping position. The angular arm 31 and the arms 15 and 16 are thus turned, so that the clamp C is moved laterally

so that said clamp is slightly distorted and it is pressed against substantially the entire adjacent surface of the flange 1, save for the reentrant portion 1a. The first and second arms 19 and 24 and link 22 then act as a self-locking device to hold said parts in the locked position. It is impossible to turn arms 15 and 16 counterclockwise from the position shown in Fig. 5, save by raising knob 29, or by turning the first arm 19 upwardly from the position shown in Fig. 5, relative to the axis of member 20. In order to open the device, the knob 29 is raised from the broken-line position shown in Fig. 5 to the full-line position thereof. This has the effect of first turning the first arm 19 until its longitudinal axis is inclined upwardly, so that the arms 15 and 16 are then freely turnable in an upward direction. This can be done by turning the arm 27 clockwise from the position shown in Fig. 5 to the position shown in Fig. 2.

It is obvious that the device is extremely simple and durable, that the knob 29 is readily accessible at all times, and that the entire device can be manipulated by one hand of the attendant. The base 2 is suitably connected to the table of an ironing machine, which is not shown, as said machine is well known per se. The drawings are substantially to scale. The device does not include a conventional toggle, because the first and second arms 19 and 24 are pivoted at spaced points to link 22, instead of being pivoted to each other at a common axis. However, the device acts to some extent like a self-locking toggle, and its action can be designated as a toggle-action.

For convenience in designating the parts in the claims, members 15 and 16 may be designated as holding means for clamp C. Said holding means turn relative to base 2, around the axis of member 12. Said axis is fixed relative to base 2. While I have shown the various parts connected to a common base, it would be equivalent to mount said parts on separate supporting members. Whenever I specify that the clamping device is used for holding the neckband of a shirt in upstanding position, the specification of such use is not intended to limit the field of use of the device.

For convenience in defining the invention, reference numerals have been used in the claims, but without limiting said claims to the preferred embodiment herein.

I claim:

1. A base comprising an upstanding flange, a resilient clamp cooperating with said flange and shaped to clamp an object against said flange, said clamp being attached to supporting means which are pivoted adjacent to and above the rear portion of said flange, a control arm 27 pivoted substantially adjacent the pivotal axis of said supporting means, a lever arm 31 operatively associated with said supporting means and extending at a fixed angular relation relative to said supporting means, a first link 22 pivotally connected to said lever arm 31, a connecting link 24 pivoted at one point thereof to the first link 22 and pivoted at another point thereof to said control arm 27, a guide means extending upwardly from said base and having abutment means below the top thereof, a spacing link 19 pivoted at one point thereof to said first link 22 and having a sliding engagement at another point thereof with said guide means, the length and arrangement of the parts being such that the control arm 27, when swung away from said base places said first link 22 and said connecting link 75

- 24 in tension to rotate said supporting means in the same direction, and when swung towards the base, the said spacing link 19 slides along said guide means until said spacing link 19 engages said abutment means to stop further sliding movement of said spacing link 19, and to form a toggle of said first link 22 and said spacing link 19 to force said clamp into operative engagement with said flange.
- 5 2. A device according to claim 1, in which said abutment means are the lower end-wall of a slot of said guide means, said slot being also closed at its upper end, said spacing link 19 having a pin which is located slidably in said slot.
- 10 3. A clamping device comprising a member having an upstanding flange, a resilient clamp which is shaped to clamp an object against said flange, said clamp being attached to supporting means which are pivoted adjacent to and above the rear portion of said flange, the pivotal axis of said supporting means being located, and said flange and clamp being shaped, so that the turning movement of said supporting means first brings the spaced points of said clamp into contact with respective spaced points of said flange and then moves the clamp laterally and also downwardly relative to said flange.
- 15 4. A base comprising an upstanding flange, a resilient clamp cooperating with said flange and adapted to clamp an object against said flange, said clamp being attached to supporting means which are pivoted adjacent to and above the rear portion of said flange, a control arm 27 pivoted substantially adjacent the pivotal axis of the supporting means, a lever arm 31 operatively associated with said supporting arm 27 and extending at a fixed angular relation relative to said control arm 27, a first link 22 pivotally connected to said lever arm 31, a connecting link 24 pivoted at one point thereof to said first link 22 and pivoted at another point thereof to said control arm 27, a guide means extending upwardly from said base and having abutment means below the top end thereof, a spacing link 19 pivoted at a point thereof to said first link 22 and having sliding engagement at another point thereof with said guide means, the length and arrangement of the parts being such that the control arm 27, when swung away from said base, places said first link 22 and said connecting link 24 in tension to rotate said supporting means in the same direction, and when swung toward the base the said spacing link slides along said guide means until said spacing link engages said abutment means to stop further sliding movement and to form a toggle of said first link 22 and said spacing link 24 to force said clamp into operative engagement with said flange, the lower end-portion of said guide means being substantially normal to the line of action of said first link 22 and of said spacing link 19 when the clamp is in its operative engagement, whereby said first link 22 and said spacing link 19 then form a self-locking toggle which maintains the clamp in said operative engagement until the control arm is swung away from said base.
- 20 25 30

WALTER A. HOCH.
